UNITED STATES PATENT OFFICE.

GAILLARD E. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS.

PISTON TOOL.

Application filed March 19, 1924. Serial No. 700,208.

My invention concerns means for supporting or stiffening or bracing a piston, such as are commonly used in internal-combustion engines or motors, particularly its internal bosses, in such a way as to prevent deformation or distortion of the piston while its wrist-pin holes or bushings are being broached out to proper size.

At the present time, it is customary to 10 broach out, rather to ream out, the wrist-pin holes of the pistons of internal-combustion engines or motors when they are originally produced or later, when, due to 15 wear or otherwise, it is desirable to increase the sizes of such holes or bearings accurately for the reception of oversize piston-pins.

During such broaching operation a very 20 substantial pressure is exerted on the piston itself through the broach, which tends to flatten or distort it, and the present invention relates to a simple adjustable tool which is designed to be inserted in the piston and 25 expanded laterally between and to bear on the adjacent faces of the internal apertured bosses, thus acting as an inner support for the piston to enable the latter to withstand the broach-operating strains without deformation or distortion.

In order that those skilled in this art may 30 have a full and complete understanding of the invention and its various advantages, in the accompanying drawing forming a part of this specification, and throughout the several views of which like reference characters 35 have been applied to the same parts, I have illustrated in detail one desirable and preferred embodiment of the invention.

In such drawing,—

Fig. 1 shows the new tool applied to a 40 piston undergoing the broaching operation, the piston being shown in central, longitudinal section, while the tool and broach are both illustrated in elevation;

Fig. 2 is an elevational view at right angles to that of Fig. 1, the piston being 45 partly broken away to illustrate the internal arrangement of the parts; and

Fig. 3 depicts the tool itself in central, lengthwise section.

Referring to the views of this drawing, 50 it will be seen that the internal-combustion motor piston 11, which is to have its piston-pin apertures accurately increased in size by broaching, has the two, usual, inwardly-extended, alined bosses 12, 12 in its interior,

the piston and bosses being apertured in alignment to receive the pair of registering, hollow bushings or sleeves 13, 13, which are forced into such apertures and firmly held in position therein by the great friction created by their introduction under substantial pressure.

It is to be assumed that the holes or bearings 14, 14 through such bushings or sleeves, and which are designed and intended to receive the piston-pin or wrist-pin, are to be broached to the required larger size by the broach 15 of known and usual construction having a plurality or series of spaced, 60 annular, cutting teeth 16, 16 of slightly progressively, gradually increasing size.

Accordingly, in order to maintain the piston in its original, perfectly round or cylindrical shape, it is necessary to support it or brace it during the broaching operation in 75 such a way as to eliminate all possibility of distortion or deformation.

This function and result the new tool easily accomplishes.

Such implement comprises the main block 80 17 which affords a bearing 18 for the reduced-diameter part 19 of a screw-threaded rod or shaft 21 having threaded engagement at 22 with a fork-shaped wedge 23 adapted to be moved away from and toward the member 17 by the turning of the rod or shaft by means of a handle 24 pinned or otherwise fixed on the protruding end thereof.

Lengthwise shifting of the shaft or rod 90 in its bearing 18 is prevented by a collar or washer 25 interposed between the shoulder 26 of the shaft and the adjacent face of the block 17, and by a second, similar washer or collar 27 between the handle 24 and the proximate face of the block.

This wedge is interposed between and contacts with a pair of tapered, fork-shaped blocks 28, 28, having plane outer faces adapted to bear against the inner surfaces 100 of the two spaced bosses 12, 12.

Each member 28 is mounted fixedly on one end of a corresponding leaf spring 29, the other end of the spring being secured against an outer face of the block 17, a rivet 105 31 conveniently fastening both such flat springs to the opposite surfaces of the block.

By turning the handle 24 and its shaft 21 in one direction, the wedge 23, by means of the threaded connection, will be drawn 110

toward the element 17 because it is prevented from turning with the shaft by reason of its engagement with the substantially stationary members 28, 28, but upon rotating the handle and shaft in the opposite direction the wedge will be forced outwardly between the converging inner surfaces of the companion or complementary outer blocks 28, 28, thereby expanding the structure or separating such pair of blocks.

During withdrawal of the wedge the two blocks 28, 28 automatically approach one another by reason of the tension of their supporting springs 29, 29, and when the two blocks are spread apart by the outward travel of the wedge between them, their outer flat faces are permitted to conform themselves accurately to any surfaces which they may engage and bear on by reason of moderate flexing of their supporting springs.

Before the broaching operation is instituted the tool, in contracted condition, is introduced into the interior of the piston with its three forked members 23, 28, 28 in such position that they will straddle and not interfere with the broach when it is inserted. If desired, they may overlie or overlap the inner ends of the sleeves or bushings which are to be broached.

Then, by turning the handle, the tool is expanded transversely by the lengthwise travel of the wedge until the flat outer faces of the tapered blocks bear firmly and truly on the ends of the bosses, which action is permitted, as explained above, by the flexure or bending of the springs 29, 29.

The tool thus acts as a solid, firm block between the two bosses, and the three parts of the tool and the bosses constitute a bridge or strut for the cylindrical piston wall, preventing its deflection or distortion or deformation during the broaching operation, which is performed in the usual and customary manner while the tool is in operative position in the piston, as explained.

Upon completion of the broaching, the tool is contracted by turning the handle, and readily removed from the piston.

As has been indicated above, during the rotation of the threaded shaft in either direction there is a tendency for the wedge-nut to turn with it, but this is precluded by its contact with the two outer blocks, resulting in the lengthwise travel of the wedge in the one direction or the other as the case may be.

An understanding of this structure will show that the tool is simple in construction, is unlikely to be injured or damaged in service, and effectively performs its intended function.

Although only one embodiment of the invention has been illustrated and described, it will be understood by those skilled in the art that it is susceptible of a variety of embodiments varying more or less in mechani-

cal details; or, stated otherwise, many minor mechanical changes may be incorporated in the structure depicted without departure from the substance and essence of the invention and without the sacrifice of any of its substantial benefits and advantages.

I claim:

1. In an appliance of the character described, the combination of a main block having a bearing therethrough, a threaded shaft extended through said bearing, a handle to turn said shaft, a forked wedge having threaded engagement with said shaft, a pair of forked tapered pressure-blocks on opposite sides of said wedge, and leaf springs secured to said main block and on which said pressure-blocks are mounted, whereby turning of the shaft shifts the wedge to effect the expansion or contraction of said pressure-blocks, the fork recesses of said wedge and pressure-blocks adapted to be in substantial register to accommodate a tool in the boss apertures of a piston with which the appliance is associated.

2. A tool of the character described comprising in combination recessed bracing means adapted to bear against the opposed inner faces of the pair of internal apertured bosses of a piston, and means to contract and expand said bracing means including a member between said boss faces and recessed in register with the recesses of said bracing means, said recesses being adapted to accommodate a tool in the apertures of said bosses.

3. A tool of the character described comprising in combination recessed bracing means adapted to bear against the opposed inner faces of the pair of internal apertured bosses of a piston, wedge means at least in part between and adapted to expand said bracing means and recessed in register with the recesses of said bracing means, said recesses being designed to accommodate a tool in said boss apertures, and spring means to contract said bracing means when permitted by said wedge means.

4. In a tool of the character described, the combination of a recessed bracing member adapted to bear against the inner face of one of the internal apertured bosses of a piston, a mounting for said member permitting it to assume a true relation to the face of said boss, and adjustable recessed means to press said member against said face, said recesses being adapted to accommodate a tool in said boss aperture.

5. In a tool of the character described, the combination of a recessed bracing member adapted to bear against the inner face of one of the internal apertured bosses of a piston, and adjustable recessed means to press said member against said face, said recesses being adapted to accommodate a tool in said boss aperture.

6. In a tool of the character described, the

combination of a recessed bracing member adapted to bear against the inner face of one of the internal apertured bosses of a piston, a spring mounting for said member permitting it to bear evenly on the face of said boss, and recessed sliding wedge means to press said member against said face, said recesses being adapted to accommodate a tool in said boss aperture.

10 7. In a tool of the character described, the combination of a pair of recessed bracing members adapted to bear against the inner faces of the internal apertured bosses of a

piston, mountings for said members permitting them to assume positions to bear evenly on the faces of said bosses, recessed wedge means between and adapted to expand said bracing members against said faces, and means to operate said wedge means, the recesses of said bracing members and wedge means being designed to accommodate a tool in the apertures of said bosses.

In witness whereof I have hereunto set my hand and seal.

GAILARD E. WEAVER. [L. S.]
